UNITED STATES PATENT OFFICE.

EDWARD A. HALBLEIB, OF ROCHESTER, NEW YORK, ASSIGNOR TO NORTH EAST ELECTRIC COMPANY, A CORPORATION OF NEW YORK.

ELECTRIC SWITCH.

1,078,195.

Specification of Letters Patent. Patented Nov. 11, 1913.

Application filed January 20, 1913. Serial No. 743,167.

To all whom it may concern:

Be it known that I, EDWARD A. HALBLEIB, a citizen of the United States, and resident of Rochester, in the county of Monroe and State of New York, have invented certain new and useful Improvements in Electric Switches, of which the following is a specification.

This invention relates to electric switches of the rotary type, and is particularly applicable to a switch such as is commonly designated as a "kick-switch", and which is employed upon an automobile in a position in which it may be operated by the foot of the driver, for the purpose of temporarily closing an electric circuit in electrical apparatus connected with an internal-combustion engine.

One object of the invention is to produce a switch of simple and inexpensive construction, in which the electric contacts are made with certainty, and in which the parts are restored to normal position automatically when the switch is released by the user.

A second object of the invention is to produce a switch adapted particularly for use in electrical installations in which it is desirable to close two circuits by a single operation of the switch but with a slight time-interval between the closing of the two circuits.

To the foregoing ends the invention consists in the construction and arrangement of parts hereinafter described, as they are defined in the appended claims.

In the accompanying drawings:—Figure 1 is a front-elevation of a switch embodying the present invention, with a portion of the cover broken away to show the interior mechanism; Fig. 2 is a vertical section on the line 2—2 in Fig. 1; and Fig. 3 is a vertical section on the line 3—3 in Fig. 2.

The invention is illustrated as embodied in a switch of which the general form is familiar, this switch having a substantially cylindrical casing 5 which is adapted to be seated in an opening in the footboard or dash of an automobile. Within the casing, at the rear thereof, is seated a circular base 6 of insulating-material, which provides a support for the fixed contacts of the switch, and which also provides a rear bearing for the shaft by which the switch is actuated. This shaft has cylindrical front and rear end-ports 7 and 8, respectively,

the part 8 being journaled in the base 6. The part 7 is journaled in a cross-bar 9, which is fixed at its ends, by screws 10, to a flange 11 on the front of the casing. The shaft is thus journaled centrally with respect to the casing. The front of the casing is closed by a removable sheet-metal cover 12, which embraces the flange 11 and is perforated to permit the shaft to project in front of the casing. On the forward end 60 of the shaft is screwed an arm 13 by which the switch may be operated.

The middle part 14 of the shaft is square, or otherwise non-circular in section, so that it may have sliding but non-rotative connection with the parts which are actuated by the shaft. One of these parts is a circular head 15 of insulating-material, to which is riveted the movable contact-member of the switch. This contact-member is 70 in the form of a spider having three equidistant fingers 16. These fingers coöperate with three fixed contacts, two of which, designated by the reference-number 17, are in the form of similar metal plates, seated 75 in recesses in the base 6 so that their forward surfaces are flush with the forward surface of the base. These plates are fixed in place by means of binding-posts 18, which pass through openings in the rear wall of 80 the casing and serve also to secure the base 85 against movement within the casing.

The fixed contact-members 17 are symmetrically disposed with relation to the fingers 16, but the third fixed contact-member 90 25, which is otherwise substantially similar to the contact-members 17, is located at a greater angular distance from the corresponding contact-finger, as shown in Fig. 3, for a purpose which will presently be described. The contact-member 25 is fixed in place by a binding-post 26, similar to the binding-posts 18.

In addition to the head 15, the squared part 14 of the shaft passes through a metal 100 shell 22, which constitutes means for connecting the shaft with one end 21 of a coiled spring 19. The other end of this spring is fixed, by means of a screw 20, to the cross-bar 9. The shell 22 is recessed, at its forward 105 surface, to receive the cross-bar 9, as shown in Fig. 1, and to provide two forwardly-projecting stop-lugs 23, which coöperate with the edges of the cross-bar. In the normal position of the parts, as shown in the 110

drawings, the spring 19 tends to hold the stop-lugs in engagement with the cross-bar as shown in Fig. 1. When the switch is to be operated the arm 13 is swung, from its right-hand position, to the left-hand position shown in dotted lines in Fig. 2, against the resistance of the spring 19, and this clock-wise rotative movement is arrested, at the proper point, by engagement of the stop-lugs 23 with the cross-bar 9 in the opposite position from that shown in Fig. 1.

In order that the contact-fingers 16 may all firmly engage the corresponding fixed contacts, the head 15 is mounted upon the shaft with sufficient looseness to permit the spider to rock slightly, if necessary, this operation being insured by the three-point engagement of the contact-fingers, under the influence of a compression-spring 24 which is coiled around the part 14 of the shaft within the shell 22. One end of this spring presses against the shell, while the other presses constantly against the head 15, thus maintaining the contact-fingers firmly against the coöperating parts.

In my co-pending application filed October 9, 1911, Serial No. 653,670, I have disclosed engine-starting apparatus embodying an electric motor-generator of a compound-wound type, this device being thrown into operation as a motor by means of an electric switch of which the contacts are so arranged that, by a continuous movement of the switch, a terminal of the motor-generator is connected with two circuit-conductors, with a slight time-interval between the formation of the two connections. The present switch is adapted for use in this connection, or in any apparatus where a similar result is required, owing to the fact that the fixed contact 25 is located at a greater angular distance from the corresponding contact finger than are the fixed contacts 17. Accordingly, when the switch is operated the contacts 17 are first connected together, and thereafter, by the continued movement of the switch, the third contact-finger is brought into engagement with the contact 25, thus connecting together all three of the fixed contacts and the conductors which may be attached to them.

The switch above described is one which may be inexpensively manufactured, and which is very easily assembled or taken apart. The head 15, the shell 22, and the shaft are all assembled by merely passing the shaft through the openings in the head of the shell, and when the cross-bar 9 has been screwed in place the mechanism is securely locked in operative condition. Since the cover-plate is not employed as a bearing-member to support the shaft, it may be removed without dismembering the mechanism, and access to or inspection of the operative parts is thus afforded through the

front of the casing while they are in their operative condition.

Although the shell 22 and the head 15 are loosely mounted on the shaft there is no possibility of the parts rattling or moving as the result of vibrations in the vehicle upon which the switch is employed, because the spring 24 acts constantly to press the shell against the cross-bar 9 and the fingers 16 against the parts with which they coöperate, so that all lost-motion is constantly taken up and the parts are held firmly in frictional engagement.

My invention is not limited to the embodiment thereof hereinbefore described and illustrated in the accompanying drawings, but may be embodied in various other forms within the nature of the invention as it is defined in the following claims.

I claim:—

1. An electric-switch having, in combination, a casing provided, at the rear, with a plurality of fixed contact-members and intermediate insulating-material lying substantially in the same plane, a shaft normal to said plane and having front and rear bearing-portions and an intermediate non-circular portion, a cross-bar removably fixed near the front of the casing and providing a front-bearing for the shaft, two rotatable members perforated to fit the non-circular portion of the shaft, whereby they are caused to rotate with the shaft but are free to move longitudinally thereon, a compression-spring between said rotatable members tending to force them apart, one of the rotatable members being thus pressed against the cross-bar while the other is forced toward the fixed contact-members, contact-fingers carried by the latter rotatable member and adapted to coöperate with the fixed contact-members, a spring connected with the other of said rotatable members and tending normally to rotate the shaft in one direction, and manually-operable means for rotating the shaft in the opposite direction.

2. An electric-switch having, in combination, a casing provided with front and rear bearings, one of said bearings formed in a cross-bar removably fixed to the front of the casing, a shaft mounted in said bearings and having an intermediate non-circular portion, a rotatable member surrounding the shaft and having a non-circular opening corresponding to the non-circular portion thereof, said member having forwardly-projecting stop-lugs adapted to coöperate with the cross-bar, contact-fingers actuated by the shaft, fixed contact-members, within the casing, adapted to coöperate with the contact-fingers, and a spring coiled about said rotatable member and fixed, at one end, to said member and, at the opposite end, to a fixed part of the switch, said spring tending to rotate the

shaft and the contact-fingers in one direction, and manually-operable means for rotating the shaft in the opposite direction, said rotation being limited in both directions by the engagement of the stop-lugs with the cross-bar.

3. An electric-switch having, in combination, a rotary shaft, a movable contact-member carried by and rotatable with the shaft and comprising three radiating contact-fingers electrically connected together, and three fixed contact-members adapted to cooperate with said fingers, respectively, when the shaft and the movable contact-member

are rotated, the fixed contact-members being 15 arranged at unequal angular distances from the corresponding contact-fingers, whereby the fingers, by a single continuous rotary movement of the shaft, act first to connect two of the fixed contact-members and then 20 to engage the third fixed contact-member and connect it with at least one of the first two fixed contact-members.

EDWARD A. HALBLEIB.
